VELOCIPED

Edward D. Fowler, Aliquippa, Pa.

Application June 18, 1934, Serial No. 731,144

3 Claims. (Cl. 208—42)

This invention relates to toys of the velocipede type and its general object is to provide a velocipede in the form to simulate a pony, horse or the like, in order to make the same attractive and 5 to add to the amusement thereof, as well as to the riding qualities.

A further object of the invention is to provide a velocipede that can be easily steered, comfortable to ride, simple in construction, inexpensive 10 to manufacture and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing where- 20 in like characters denote like or corresponding parts throughout the several views, and in which:

Figure 1 is a side elevation of the velocipede that forms the subject matter of the present invention.

Figure 2 is a sectional view taken approxi- 25 mately on line 2—2 of Figure 1.

Figure 3 is a sectional view taken approxi- 30 mately on line 3—3 of Figure 2.

Figure 4 is a perspective view of the upper 35 portion of the sleeve of the fork of my device.

Figure 5 is a similar view of the upper portion of the pivot rod.

Referring to the drawing in detail, it will be noted that my velocipede is in a form to simulate 40 a pony or horse, but it can be in any desired form, as will be apparent.

The body is indicated by the reference numeral 1 and depending at a rearward inclination from the body are the rear legs 2 that have 45 extending therethrough and adjacent to the lower ends thereof an axle 3, the latter having journaled thereon wheels 4. While it is my intention to have two rear wheels, a single rear wheel may be employed. The body 1 has preferably arranged thereon a saddle 5 and stirrups together with the usual straps may be used with the saddle.

The forward portion of the body has arranged 50 vertically therein a bore through which passes the sleeve 6 of a fork 7, the fork including the usual spaced parallel arms which in the present instance has secured to the outer surfaces thereof, members 8 which are shaped to simulate the front feet and legs of a pony or horse.

55 The arms of the fork adjacent to their lower

ends, as well as the members 8 are each provided with slots extending through the inner edges thereof, and arranged upwardly at an inclination, as shown in Figure 1, so that the inner ends of the slots provide bearings for the 5 axle 9 of the front wheel 10, the axle having secured thereto the crank and pedal construction 11. By providing the slots, it will be obvious that the axle 9 and the crank portions for the 10 pedals can be made in one piece, and easy assemblage thereof with respect to the fork is then possible, merely by sliding the axle in the slots.

A shoulder is provided at the juncture of the arms 7 with the sleeve 6 and mounted upon the 15 shoulder is a washer 12 that acts as a bearing, as will be apparent upon inspection of Figure 2. The sleeve extends through the bore and has arranged in its upper end a pair of diametrically opposed longitudinally arranged slots 13 that extend through the upper end for the purpose of 20 accommodating a handle bar 14 which is passed through the upper end of a rod 15 as clearly shown in Figure 2. The rod 15 has a threaded lower end for the purpose of receiving a nut for 25 connecting the rod with respect to the sleeve, through the instrumentality of the handle bar 14, as it will be apparent upon inspection of Figure 2, that the nut holds the handle bar 14 within the 30 slots 13.

The rod and sleeve likewise extend into a recess arranged in the neck portion 16 of the head 17 and the neck is provided with a bore transversely arranged therethrough for the purpose of receiving the handle bar 14, the latter having the 35 usual grips secured to the ends thereof. Disposed between the confronting faces of the neck and top of the body are washers 18 that act as bearings as will be apparent.

The head may have painted or otherwise 40 formed thereon, a bridle as shown, and the body, neck, and leg portions may be decorated in any well known manner.

From the above description and disclosure of 45 the drawing, it will be obvious that I have provided a velocipede in the form of an animal and preferably a pony, which of course adds materially to the amusement of the toy, as well as to the attractiveness thereof.

It is thought from the foregoing description 50 that the advantages and novel features of my invention will be readily apparent.

I desire it to be understood that I may make 55 changes in the construction and in the combination and arrangement of the several parts, pro-

vided that such changes fall within the scope of the appended claims.

What I claim is:

1. A wheeled toy comprising a body, neck, head and leg portions to simulate an animal, propelling and steering means for the toy and including a fork, crank and pedal means including a front axle extending through the arms of the fork, a front wheel secured to the axle, a sleeve formed on the fork and rising therefrom for disposal through the body and receivable in the neck portion, and a handle bar extending through the neck portion and being detachably connected to the sleeve.
- 10 2. A wheeled toy comprising a body, neck, head and leg portions shaped to simulate an animal, propelling and steering means for the toy and including a fork, crank and pedal means including an axle journaled in the fork, a wheel secured to the axle, a sleeve formed on and rising from the fork and having longitudinally disposed diametrically arranged slots in its upper end, said sleeve extending through the body and terminating in the neck portion, a rod extending through

the sleeve and being secured therein, and a handle bar secured in the upper end of the rod and extending through the slots for detachable connection with respect to the sleeve.

3. A wheeled toy comprising a body, neck, head and leg portions shaped to simulate an animal, propelling and steering means for said toy and including a fork having the front leg portions secured to the outer surfaces of the arms of the fork, crank and pedal means including an axle 10 detachable with and passing through the arms and front leg portions, a wheel fixed to the axle, a sleeve formed on and rising from the arms and extending through the body, said sleeve having diametrically opposed slots extending through the 15 upper end thereof, a rod fixed to said sleeve and extending therethrough, a handle bar extending through the upper end of the rod and slots respectively for detachable connection with the sleeve, said handle bar extending through the 20 neck portion, and bearings between the neck portion and body and between the latter and the fork.

EDWARD D. FOWLER.
